UNITED STATES PATENT OFFICE.

BURDON P. HYDE, OF WATERBURY, CONNECTICUT, ASSIGNEE TO SCOVILL MANUFACTURING COMPANY, OF WATERBURY, CONNECTICUT, A CORPORATION OF CONNECTICUT.

LOOSE-POWDER VANITY BOX.

Application filed September 17, 1923. Serial No. 663,025.

This invention relates to certain improvements in small boxes or cases for holding cosmetics and commonly known as vanity boxes, in which provision is made for holding a cosmetic in powdered form.

It is the especial object of the present invention to improve the construction of this type of box so as to make the box strong and to effect a convenient distribution of loose powder therefrom, the box of the present invention being so constructed as to be entirely proof against accidental leakage of powder, particularly around the catch and at the hinge. It is a further object of the invention to provide a fitment for holding the powdered cosmetic which is easily removed from and inserted in a box so that the fitment may be used in place of a compact (that is cosmetic in a compact form) when desired.

With these and other objects not specifically referred to, the invention consists in certain novel parts, arrangements and combinations, which will be fully described in connection with the accompanying drawings and the novel features thereof pointed out in the claims hereunto appended.

In the drawings—

Figure 1 is a face view of a powder box for holding loose powder only, the box being shown with the cover open and the powder compartment closed;

Figure 2 is a sectional view taken through the catch and spring of Fig. 1, showing the box closed;

Figure 3 is a sectional side view showing the box open and one form of powder holding fitment associated therewith;

Figure 4 is a detail sectional view, partly broken away on an enlarged scale.

Figure 5 is a sectional side view of a double box, a box holding two kinds of cosmetic in compact form;

Figure 6 is a sectional side view of the double box of Fig. 5, in which one of the compacts has been displaced by the loose powder holding fitment;

Figure 7 is a perspective view of one form of fitment with a cover frictionally associated therewith;

Figure 8 is a similar view with the cover removed;

Figure 9 is a similar view of the cover.

Referring now to these drawings, there is illustrated a fitment and box for holding loose powder so that powder cannot escape therefrom except when desired for use, which fitment and box may be used with but one cosmetic in a powdered form, and a box capacitated to hold two cosmetics in a compact form, one or both of which may be replaced with the loose powder holding fitment.

Referring first to Figs. 1 to 4, there is shown the box and fitment for holding but one cosmetic in a powdered form. The box illustrated includes a bottom member 1 having an upstanding peripheral wall 2, this wall at its upper edge being inset to form an abutment or shoulder 3 and a flange 4 extending thereabove. Pivottally associated as or by a hinge 6 is a cover 7, this cover member being provided, as is usual, with a downwardly extending flange 8 adapted to telescope over the flange 4 and abut against the shoulder 3 when the parts are in closed position. This cover is or may be provided with a mirror 9 held in position in the cover by a holding flange 10.

The bottom member 2 of the box is in the particular box illustrated, the powder carrier, and in accordance with the invention this bottom member is provided with a powder carrying fitment and cover therefor so constructed and arranged as to be leak proof except through certain powder dispensing orifices provided for the purpose. In accordance with the invention there is provided a fitment in the form of a ring having a bottom 11 and an upstanding continuous vertical flange 12 bevelled or flared outwardly as indicated at 13. At its upper portion this outwardly flared part 13 terminates in a rim 14 from which depends a downwardly extending flange 15, this cup being held in the bottom 2 preferably by frictional engagement of the flange 15 with the flange 4 of the bottom before referred to.

Co-operating with this fitment is a cover which in the construction shown in Figs. 1 to 4 is pivotally associated with the cup, this cover being hinged to the rim 14 of the cup by means of a hinge 17. This cover is formed so as to co-operate with the cup walls and produce a powder tight joint therewith when the cover is closed. In the con-

struction shown the cover is provided with a downwardly extending inset flange 18 and above the flange with a bevelled rim 19. The flange 18 and the rim 19 have a very tight fit with the flanges 12 and 13 of the cup. These flanges being arranged as shown at an angle to each other provide a powder tight joint and working of the powder between these parts is effectively prevented.

- 10 The central portion of the cover is disposed below the rim 19 so as to form a space between it and the mirror for the accommodation of a puff. The central portion of the cover is formed slightly concave, as indicated at 20 in Fig. 2, and is provided with a number of small perforations 21 through which powder may be sifted on to the puff, surplus powder owing to the concavity tending to sift back into the cup.
- 20 The parts may be held in closed position by means of a spring catch, indicated at 22, this catch being operated by a button 23, the rim 14 of the cup being partially cut, as indicated at 24 to permit the catch to work.
- 25 If desired the cover 16 may be provided with a bent up portion 25 by which it may be grasped and readily lifted from closed position to permit access to the cup.

It will be seen that with the construction described a continuous unbroken wall is provided for the powder compartment at and below the cover 16 when the cover is closed, and at the same time provision is made for hinging the cover 16 and for the catch. The powder, however, because of the continuous bottom and side flanges of the cup cannot escape except through the distributing orifices provided in the cover. While these distributing orifices are preferable, it will be understood they may be omitted.

Referring now to Figs. 5 to 9 there is shown a box for holding two cosmetics in a compact form and a fitment which may be used to replace one or both of the compacts. In the box shown there is provided a cover 27, which may be provided with a mirror 28, and a bottom member 29 pivotally associated with the cover on a hinge 30. This bottom member 29 is provided with a removable holder 31 for holding a cosmetic compact as a rouge pad 32, on a plate 33.

Also associated with the cover and bottom members, preferably by pivoting on the hinge 30, is a central partition member 34 having a bottom 35 and a peripheral flange 36 which is inset at 37 and 38 to form an abutment or rib 39 against which the flanges of the cover and bottom members abut when in closed position. This central member 34 is arranged to carry a cosmetic compact as a powder pad 40, space being left above the pad and below the mirror for a puff. This pad is frictionally held in position as by spring fingers 41 on a plate 42 interposed

between the bottom 35 and the compact plate 43, these fingers taking under shoulders 44 formed by insetting the flange 36.

This compact is thus removably held in the box and may be replaced by the loose powder holding fitment as described above, the flange 15 of the fitment having frictional engagement with the inner side of the flange 36. While if desired a fitment having a cover pivotally associated therewith may be used in this connection, a fitment such as shown in Figs. 7 to 9 may be employed in which the cover is frictionally engaged with the fitment, such a cover being indicated at 45.

While the invention has been shown and described in its preferred form, it will be understood that various changes may be made in the construction, arrangement and material of the box without departing from the invention as defined by the claims hereunto annexed.

What I claim is:

1. A vanity box having in combination a member having a peripheral wall or flange and forming a holder, a cover associated therewith, a bodily removable loose powder containing fitment held in the holder and having a peripheral wall and a bottom, said wall flaring towards its upper edge and terminating in a rim, a lid associated with the fitment and having frictional engagement with and below the flaring portion of the wall, said lid being provided with means for dispensing powder from the fitment, and means for frictionally engaging the fitment in the box.

2. A vanity box having in combination a bottom member having a peripheral wall or flange and forming a holder, a powder holding fitment held in the holder having a continuous wall, a bottom, and a rim offset from the wall, a lid hinged in the rim having frictional engagement with the fitment wall, a cover having telescoping engagement with the bottom member, a slot in the outer edge of the rim and a catch working in the slot for securing the cover and bottom members together.

3. A loose powder fitment readily removable from and replaceable in vanity cases comprising a container having a bottom and a peripheral wall, said wall flaring at its upper end, a cover associated with the fitment, said cover having a flaring flange for frictional engagement with the container wall, and an integral flange outside and concentrically parallel with the wall for frictionally engaging the container in a box.

4. A loose powder fitment for vanity boxes comprising a container having a peripheral wall and a bottom, a rim offset from the wall, a cover pivoted to the rim outside the wall, an integral flange outside

- and concentrically parallel with the wall for frictionally engaging the container in a box, and a slot in the outer edge of the rim for engaging a cooperating catch.
5. A loose powder fitment readily removable from and replaceable in vanity boxes comprising a container having a peripheral wall and a bottom, said wall being flared at its upper end, a cover associated with the container, said cover having a flaring flange in frictional engagement with the wall, and having a depressed portion provided with powder distributing openings.
10. A vanity box having in combination a bottom member having a peripheral wall or flange and forming a holder, a powder containing fitment held in the holder and having a continuous wall and a bottom, said wall having a rim offset therefrom, a lid pivotally associated with the fitment and having a portion depressed below the rim to provide a pocket for a powder puff and formed with powder distributing openings, said lid having a flange in frictional engagement with the wall of the fitment and a cover over the lid.
15. A vanity box having in combination a bottom member having a peripheral wall or flange and forming a holder, a powder containing fitment held in the holder and having a continuous wall and a bottom, said wall having a rim offset therefrom, a lid pivotally associated with the fitment and having a portion depressed below the rim to provide a pocket for a powder puff and formed with powder distributing openings, said lid having a flange in frictional engagement with the wall of the fitment and a cover over the lid.
20. A loose powder fitment readily removable from and replaceable in a vanity case comprising a container having an imperforate bottom and a peripheral wall for frictional engagement with the case, a flange extending inwardly and downwardly from the wall, and a cover cooperating with the flange and controlling the dispensing of powder from the fitment.
25. In a vanity box, the combination of a bottom, a cover associated therewith, an intermediate compartment, a rouge compact in one of the compartments, and a bodily removable loose powder fitment frictionally engaged in the other compartment, an inwardly and downwardly extending flange, said fitment being provided with a cover having powder tight engagement with the flange of the fitment and arranged to provide for the dispensing of loose powder from the fitment.
30. In a vanity box, the combination of a bottom member and a closure associated therewith, a compact carried in one of these members, and a loose powder fitment 40 removably carried by the other of the members, said loose powder fitment having its own cover associated therewith in powder 45 tight relation.
35. A loose powder fitment readily removable from and replaceable in a vanity case comprising a container having an imperforate bottom and a peripheral wall for frictional engagement with the case, a flange extending inwardly and downwardly from the wall, and a cover cooperating with the flange and controlling the dispensing of powder from the fitment.
40. In testimony whereof, I have hereunto set my hand.
45. BURDON P. HYDE.
